UNITED STATES PATENT OFFICE.

WILLIAM S. ROSECRANS, OF SAN FRANCISCO, CALIFORNIA.

EXPLoder FOR BLASTING-CHARGES.

SPECIFICATION forming part of Letters Patent No. 230,820, dated August 3, 1880.

Application filed February 6, 1879.

To all whom it may concern:

Be it known that I, WILLIAM S. ROSECRANS, of the city and county of San Francisco, and State of California, have invented a new and useful Improvement in Exploders for Blasting Purposes; and I hereby declare that the following is a full, clear, and exact description of the same, reference being had to the accompanying drawings, in which—

10 Figure 1 is a side view, and Fig. 2 a section, of the exploder with the fuse in place.

15 My invention is specially applicable to be used in connection with that class of powders—such as the giant, Hercules, and others—which require a powerful concussion in order to produce an explosive ignition.

20 Hitherto a large cap filled with a powerful fulminate or percussive powder has been employed, which, with a fuse attached, has been embedded in the charge; but these caps contain so much fulminate that they are themselves dangerous, on account of the ease with which they may be exploded.

25 My invention consists of an exploder formed of a tube of metal capable of holding the enclosed powder, when ignited, under considerable pressure, in combination with a powder-filling incapable of explosion except when ignited within a case capable of holding it under pressure; and, second, it consists in the peculiar manner of holding the fuse within the tube and the exploding powder under pressure.

30 I prefer to use with my exploder powders such as that described in the patent granted 35 to Hafenegger, February 7, 1871, No. 111,642.

The shell of the exploder is of a shape shown clearly in the drawings. It is a strong metallic tube closed at one end and open at the other. Into this tube I introduce the powder, 40 (represented at B,) which, if ignited without confinement will simply burn out without exploding, and which therefore may be safely handled or transported in the exploder.

In order to insure the explosion of the charge I use a wad of paste of ordinary gunpowder 45 or equivalent substance, which may be rolled into thin sheets and cut into disks C of a size to fit the tube. This disk or wad is pressed into the tube upon the powder, and serves to hold the latter in place, and also to insure the 50 ignition of the same by serving as a medium of communication between the fuse and powder.

When these exploders are to be used the fuse D is pushed into the open end of the tube, which is left empty for a space for that 55 purpose. The fuse should be pushed down until it touches the wad C, and the tube is then pinched or compressed, as shown at x, upon the fuse, so as to hold it firmly in place. This serves to hold the powder under confinement, so that when ignited the gases will be held under pressure and an explosion caused 60 sufficiently powerful to ignite powder of the class heretofore specified.

I am aware of the patent of Castellanos of 65 July 24, 1877, No. 193,485, and desire to be understood as not claiming anything shown therein; but,

Having thus described my invention, what I claim is—

1. An improved exploder, consisting of a strong tube containing a powder incapable of explosion except when ignited under confinement, said tube being adapted for connection with the fuse and to hold the powder under 75 confinement, as set forth.

2. The improved exploder consisting of the metal case filled with powder capable of exploding only when ignited under confinement, in combination with the fuse inserted therein, said case being indented upon the fuse, as set forth.

W. S. ROSECRANS.
